(57) **CLAIM**

I claim, the ornamental design for an exterior surface configuration of a vehicular taillight, as shown and described.

DESCRIPTION

FIG. 1 is a perspective view of an exterior surface configuration of a vehicular taillight showing my present design; FIG. 2 is a front view thereof; FIG. 3 is a left view thereof; and, FIG. 4 is a top plan view thereof.

The broken line showing of a portion of the automobile is included for the purpose of illustrating only and forms no part of the claimed design.
